ROSWELL A. MOORE, OF KENSINGTON, CONNECTICUT.

Design No. 4,709, dated March 14, 1871.

DESIGN FOR A GARDEN-TOOL.

The Schedule referred to in these Letters Patent and making part of the same.

To all whom it may concern:

Be it known that I ROSWELL A. MOORE, of Kensington, county of Hartford, and State of Connecticut, have invented or discovered certain new and useful Design for a Miniature Garden-Tool.

And to enable others skilled in the art to make the same, I will proceed to describe, referring to the drawings, in which the same letters indicate like parts.

In the accompanying drawings—

d is a two-pointed earth loosener, punched or cut from sheet metal, having a wire shank, e”, plain elongated handle f”, embellished with a ferrule, g”, struck up from sheet metal, to produce a design for a miniature garden-tool.

What I claim, and desire to secure by Letters Patent, is—

The design for a miniature garden-tool, substantially as set forth.

ROSWELL A. MOORE.
